Primary Examiner — Selina Sikder(74) *Attorney, Agent, or Firm* — ZANIP(57) **CLAIM**

The ornamental design for a remote controlled socket, as shown and described.

DESCRIPTION

FIG. 1 is a first perspective view of a remote controlled socket showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

(Continued)

The broken lines shown in the drawings depict portions of the remote controlled socket in which the design is embodied that form no part of the claimed design.
